INVENTOR.

BY Fedor Stiyouk
George C. Heinrichs
ATTORNEY.

UNITED STATES PATENT OFFICE.

FEDOR STIYOUK, OF NAROL, CANADA.

LAMP EXTINGUISHER.

Application filed August 9, 1922. Serial No. 580,683.

To all whom it may concern:

Be it known that I, FEDOR STIYOUK, a citizen of Ukrainia, residing at Narol, Province of Manitoba, and Dominion of Canada, have invented certain new and useful Improvements in Lamp Extinguishers, of which the following is a specification.

The present invention relates to improvements in lamp extinguishers, and it is the principal object of the invention to provide an attachment combined with the wick operating rod allowing a ready application of the attachment to any ordinary lamp now in use without great expense.

15 A further object of the invention is the provision of a novel lamp attachment of an extremely simple and inexpensive construction.

These and other objects of my invention will become more fully known as the description thereof proceeds, and will then be more specifically pointed out in the appended claim.

20 In the accompanying drawing, forming a material part of this disclosure:

Figure 1 is the front view of a lamp burner equipped with the attachment constructed according to the present invention.

Figure 2 is a side view thereof.

25 Figure 3 is a top plan view of a burner, and

Figure 4 illustrates in perspective detail view the lamp attachment.

The lamp burner 10 of any desired type and material is provided with the customary perforated plate 11 and wick tube 12 through which the wick 13 is guided in the usual manner adapted to be fed by the operation of rod 14 and knob or disc 15.

30 All the parts described so far are commonly well known in the art and do not form any part of my invention, which I will now describe.

The rod 14 carries rotatably a sleeve 16 equipped at one end with a disc 17. At its opposite end the sleeve 16 is provided with

a lip 18 having a perforation near its outer end in which is secured the hooked lower end 19 of a bar 20 having a shoulder 21 rectangularly disposed to bar 20 and bent upwardly to form an upright link 22 passing through a slot 23 in plate 11, and secured with its upper hook shaped end in a hole or perforation of a lever 24, integrally made with a cap 25 provided with lateral shoulders or extensions ending in pins 27, rectangularly disposed to said shoulders by means of which the cap is pivotally secured to the wick tube 12.

A small leaf spring 28 is secured with one end to the burner, and its opposite free end is engaging the lower face of shoulder 21 and has the tendency to press the lever 22 upwardly so that after the release of disc 17, the cap will return automatically into its position of rest.

In operation, the disc 17 is rotated in the direction of the arrow, this operation will swing cap 25 over the wick and extinguish the flame, after this has been done, and the grip on disc 17 is released, the cap will, as described above, be automatically returned into its position of rest.

Having thus described my invention, what I claim is:

35 In a lamp extinguisher of the class described, a rotatable sleeve, a disc at one end of said sleeve for rotating the same in one direction, a perforated lip at the opposite end of said sleeve, a shouldered lever secured with one end to said lip, a cap to which the other end of said lever is secured adapted to be swung into extinguishing position upon the rotation of said disc and sleeve in one direction, and a spring engaging the shoulder of said lever for automatically returning the parts into their normal position of rest after each extinguishing operation.

40 In testimony whereof I have affixed my signature.

FEDOR STIYOUK.
